W. LEMB.
PIPE PROTECTOR.
APPLICATION FILED OCT. 30, 1915.

Patented Mar. 28, 1916.

Inventor
William Lemb.

By Mr. Attorney

William H. Reid

UNITED STATES PATENT OFFICE.

WILLIAM LEMB, OF BROOKLYN, NEW YORK.

PIPE-PROTECTOR.

1,177,256.

Specification of Letters Patent. Patented Mar. 28, 1916.

Application filed October 30, 1915. Serial No. 58,935.

To all whom it may concern:

Be it known that I, WILLIAM LEMB, a citizen of the United States, and resident of Brooklyn, in the county of Kings and State 5 of New York, have invented certain new and useful Improvements in Pipe-Protectors, of which the following is a specification.

This invention has reference particularly to coverings for the blow-off pipes for steam 10 boilers, where the pipe extends downward from the boiler a short distance, and then has an L from which the pipe extends horizontally rearward or to one side of the furnace.

15 The object of the present invention is to provide an improved form of protector or covering for the deflected pipe, that can be readily assembled and secured in position, and which will entirely protect the pipe 20 from the heat and gases of the furnace, and which at the same time can be readily disassembled by simply removing a few members for inspection of the pipes, and the removed parts quickly and readily replaced, 25 and the covering restored to former condition.

In the accompanying drawing illustrating 30 one embodiment of my invention, Figure 1 shows the invention applied to a boiler furnace. Fig. 2 is a similar view with some of the blocks removed. Fig. 3 is an elevation, and Fig. 4 a plan of one of the L block sections; and Fig. 5 shows one of the other pipe sections.

35 As shown in the drawings, the boiler 6 has a depending pipe 7 connecting with a horizontal pipe 8 by an L 9, which constitutes the blow-off for the boiler, the pipe 9 extending through the rear wall 10 of the 40 furnace. For the straight pipe portions 7 and 8 I use complemental sections 12 of substantially semi-cylindrical, or semi-tubular form, one of which is shown separately in Fig. 5. The opposite end faces are 45 tongue and grooved at 13 and 14 respectively for interlocking engagement, and the flat or diametral faces of the two blocks that engage when placed around the pipe, are also tongue and grooved at 15 and 16 as indicated, to provide a tight joint. To secure 50 these sections on the pipe I provide a number of longitudinally extending bores 11, two being shown in each section a quadrant's distance removed. When these sections 12 are placed around the pipe 8, with the engaging faces in adjacent blocks removed a

quadrant's distance to break joints, these bores 11 will register, and can receive rods 17, that may be solid or tubular as desired. In the act of assembling these sections 12, 60 the rods can be advanced as each additional section is placed in position and thus serve to hold them in their proper place. The upright pipe 7 can also receive the same block sections 12' placed in a similar manner, but 65 the guide rods are not needed here as will presently appear.

At the L pipe joints I provide a pair of complemental block sections 18 and 19. These sections when brought together have 70 a central enlarged opening 20 for the L of the pipe, and smaller openings at 21 and 22 for the two pipes that engage the L. The flat engaging faces of these two sections are provided with tongue and groove 75 portions, 23 and 24 respectively, adapted for interlocking engagement. It will be seen from Figs. 1 and 2 that these two blocks have their engaging faces extending vertically and alining with the horizontal pipe 80 8. The faces 25 and 26 of these blocks that engage the adjacent block sections 12, are shown provided with tongues 27, that engage the grooves 14 of the sections 12 to interlock with the same. These block sections 18 and 19 are further provided with 85 bores 28 that register with the bores 11 of the sections 12, for the purpose of receiving the rods 17, as indicated in Fig. 2. These rods thus serve not only to lock the straight 90 pipe sections in position, but also will hold the L sections in proper place around the L. However, if desired additional locking means may be provided at the outer portion 95 of the sections 18 and 19. As shown I provide register bores 29 in these sections, through which a bolt member 30 can be inserted and secured to screw the sections tightly together. The outer ends of the 100 bores 29 can be slightly enlarged and receive the asbestos cement to protect the bolts. Also the bores 28 can be closed with cement to protect the ends of the rods from action of the fire and gases.

The upper faces 31 of the block sections 18 and 19 may be provided with a tongue 32 to interlock with the sections 12' that are placed on top of the L blocks, as shown in Fig. 1, thus interlocking and forming a tight joint with the L blocks. These sections are continued upward as far as they can be inserted beneath the boiler, and the

remaining space filled with fireproof cement 33, to entirely protect the blow-off pipe. The other sections 12 are continued to the wall 10, and may extend into an opening in the same and be cemented therein in the usual manner. The L sections 18 and 19 may also be provided with registering openings 34 in the bottom portion, and a number of the block sections 12² be placed below the 10 L sections to form a support for these blocks, as indicated in Fig. 1. The lower face of the L sections has a groove 35 for interengagement with these block sections 12². This will serve to close the opening 34 and protect the L section. But if desired these blocks 12² can be omitted, and the opening 34 closed by the usual asbestos cement.

In the use of my improved covering, the sections 12 are first placed around the horizontal pipe 8, and the rods 17 inserted as the blocks are added, from the joint to the wall. The two L blocks 18 and 19 are placed around the L, and then the rods extended into the bores in these blocks which will hold them in position. Then the additional bolt 30 if employed, is inserted and tightened to secure the L blocks. The upper block sections 12² are then added and the pipe closed up to the boiler. Next the lower sections are placed in position if desired; or else the opening 34 can be closed by cement.

When it is desired to inspect the joint it is only necessary to remove the lower blocks 12², or clear the opening 34, when the L is visible, and the hand can be inserted to examine it for leaks. But if a closer inspection is needed the bolt is removed and the two rods on one side are withdrawn, whereupon one of the blocks as 19 can be withdrawn, and replaced when desired. It will be understood that no metal parts are employed, except the rods 17, and sometimes the bolt 30; and those parts are covered by asbestos cement, that completely protect such parts from the action of the heat and gases. These blocks are made of suitable refractory material, such as fire clay, asbestos or similar substances.

Having thus described my invention, what I claim is:

1. In a pipe protector, the combination of a series of complemental block sections for the straight pipe that have longitudinal registering bores, rods extending through the bores to hold the sections in position, and a pair of complemental L block sections with vertical engaging faces extending parallel with the straight pipe sections, the L block sections having horizontal bores that register with said pipe section bores and receive said rods that thereby lock the L sections in position adjacent said sections to inclose a pipe L.

2. In a pipe protector, the combination of a series of complemental block sections

for the straight pipe that have longitudinal registering bores, rods extending through the bores to hold the sections in position, a pair of complemental L block sections with vertical engaging faces extending parallel with the straight pipe sections, the L block sections having horizontal bores that register with said pipe section bores and receive said rods that thereby lock the L sections in position adjacent said sections to inclose a pipe L, and a locking member directly connecting the said L block sections at their outer portions.

3. In a pipe protector, the combination of a series of complemental block sections for the straight pipe that have longitudinal registering bores, rods extending through the bores to hold the sections in position, a pair of complemental L block sections with vertical engaging faces extending parallel with the straight pipe sections, the L block sections having horizontal bores that register with said pipe section bores and receive said rods that thereby lock the L sections in position adjacent said sections to inclose a pipe L, said L sections having transverse registering bores, and a bolt in said bores securing the two sections together.

4. In a pipe protector, the combination of a series of complemental block sections for the straight pipe that have longitudinal registering bores, rods extending through the bores to hold the sections in position, a pair of complemental L block sections with vertical engaging faces extending parallel with the straight pipe sections, the L block section having horizontal bores that register with said pipe section bores and receive said rods that thereby lock the L sections in position adjacent said sections to inclose a pipe L, and complemental block sections for the pipe above the L sections that have interlocking engagement with the said L sections.

5. In a pipe protector, the combination of a series of complemental block sections for the straight pipe that have longitudinal registering bores, rods extending through the bores to hold the sections in position, a pair of complemental L block sections with vertical engaging faces extending parallel with the straight pipe sections, the L block sections having horizontal bores that register with said pipe section bores and receive said rods that thereby lock the L sections in position adjacent said sections to inclose a pipe L, and complemental block sections below the said L sections having interlocking engagement with the same and adapted to support the sections from the base.

6. In a pipe protector, the combination of a series of complemental block sections for the straight pipe that have longitudinal registering bores, rods extending through the bores to hold the sections in position, and a pair of complemental L block sections with

vertical engaging faces extending parallel with the straight pipe sections, the L block sections having horizontal bores that register with said pipe section bores and receive 5 said rods that thereby lock the L sections in position adjacent said sections to inclose a pipe L, said L blocks having the bottom portion open at the center for access to the pipe L, and adapted to receive a removable closure for the L blocks.

7. In a pipe protector, the combination of

complemental block sections for the straight pipe, securing means to hold the sections in position, and a pair of complemental L block sections with vertical engaging faces 15 extending parallel with the straight pipe sections, said securing means being also arranged to lock the L sections in position adjacent said straight pipe sections to inclose a pipe L.

WILLIAM LEMB.
